UNITED STATES PATENT OFFICE.

WILLIAM M. ONEY, OF HOUSTON, TEXAS.

OIL AND GAS BURNER.

1,416,574.

Specification of Letters Patent. Patented May 16, 1922.

Application filed May 20, 1920. Serial No. 382,843.

To all whom it may concern:

Be it known that I, WILLIAM M. ONEY, citizen of the United States, residing at Houston, in the county of Harris and State 5 of Texas, have invented certain new and useful Improvements in an Oil and Gas Burner, of which the following is a specification.

This invention relates to new and useful improvements in an oil and gas burner.

10 One object of the invention is to provide a burner of the character described which is specially adapted for the purpose of utilizing oil or gas as a fuel and which may be readily adjusted for the use of one or the 15 other of said fuels as desired.

Another object of the invention is to provide a burner which while utilizing oil as a fuel is also adapted to consume the gas which collects in the fuel tank and which 20 would otherwise be wasted.

A further feature of the invention resides in the provision of an agitator having spiraled vanes and rotatably mounted within the nozzle whereby a more perfect mixture 25 of fuel and air is obtained.

A still further feature of the invention resides in the provision of a means for introducing auxiliary air and mixing the same with the fuel.

30 A still further feature of the invention resides in the provision of a means for readily cleaning out the burner without the necessity of taking the same apart.

With the above and other objects in view, 35 the invention has particular relation to certain novel features of construction, operation and arrangement of parts, an example of which is given in this specification and illustrated in the accompanying drawings, 40 wherein—

Figure 1 is a longitudinal, sectional view, Figure 2 shows a side view of the nozzle tip with the agitator mounted thereon,

Figure 3 shows a transverse, sectional view, taken on the line 3—3 of Figure 1,

Figure 4 shows a transverse, sectional view taken on the line 4—4 of Figure 1,

Figure 5 shows a transverse, sectional view taken on the line 5—5, of Figure 1,

50 Figure 6 shows a transverse, sectional view taken on the line 6—6 of Figure 1,

Figure 7 shows a transverse, sectional view, taken on the line 7—7 of Figure 1,

55 Figures 8 and 9, respectively show modified forms of nozzle tips.

Figure 10 shows a side elevation of the burner,

Figure 11 shows a side view, partially in section, of a modified form of the burner and,

Figure 12 shows a fragmentary sectional view taken on the line 12—12 of Figure 1.

Referring now more particularly to the drawings, wherein like numerals of reference designate similar parts in each of the figures, 65 the numeral 1 refers to a stationary tapering shell, whose large end is formed with the surrounding annular flange 2 and fitted through this shell there is a burner casing 3, one end of which is formed into the reduced 70 neck 4 and the other end 5 of which extends beyond the shell. This casing has a central passageway through which the fuel pipe extends and at one end this pipe is surrounded with a stuffing box 7 contained within the 75 neck 4, while at the other end the passageway is enlarged, forming an internal steam chamber 8, which surrounds the pipe 6. Threaded on to the end 5 of the casing there is a tubular nozzle casing 9 having the passageway 10 and the mixing chamber 11, and this nozzle casing is provided with a discharge nozzle 12 of any desired form. Within the chamber 11 there is a nozzle tip 13. This tip may be of different forms, 80 some of which are shown in Figures 1, 2, 8 and 9 and the form of the nozzle 12 should be varied to conform to the form of tip employed. This tip is screwed on to the inner end of the fuel pipe 6 and has an enlarged 85 section 14 provided with peripheral spiralled grooves 15 and is also provided with the radiating discharge ports through which the fuel delivered through the pipe 6 is discharged into the passageway 10. Rotatably 90 mounted upon the tip 13 there is an agitator 17 formed with radiating spiralled vanes 18 and behind this agitator there are the auxiliary air inlets 19 through which air may be admitted into the mixing chamber of the 100 nozzle casing. The shell 1 is provided with two steam inlets 20, 20 and with two fuel inlets 21, 21. These inlets are shown oppositely disposed, in Figure 1, for the sake of better illustration. But in actual practice 105 the steam inlets as also the fuel inlets will be arranged about 120 degrees apart. One of the fuel inlets is provided for the admission of oil as a fuel and the other is provided for the admission of gas as a fuel. The 110

burner casing 3 has the steam port 22 adapted to register with either of the steam inlets and to admit steam into the chamber 8. The burner casing also has a fuel port 23 adapted to be brought into registration with either of the fuel inlets 21 and through which fuel is admitted into the pipe 6, when the latter is in forward position, so as to bring the port 24 therethrough into registration with said port 23. The burner casing has a conduit 25 leading from the gas inlet 26 and extending on through the nozzle casing and discharging into the mixing chamber. This conduit is controlled by the valve 27. When oil is being used, as a fuel the surplus gas which collects in the oil tank is conducted through a suitable pipe and discharged into the conduit 25 and the pressure will lift the valve 27 and said gas will be admitted into the mixing chamber 11 and will be utilized. In common practice this surplus gas is wasted. A coil spring 28 surrounds the projecting end 5 of the burner casing and is interposed between the adjacent end of the nozzle casing and the shell 1 and by its pressure holds said shell seated tightly on the burner casing. Detachably secured to the neck 4 and upstanding therefrom there is a standard 29, pivoted to the front side of which there is a hand lever 30, whose lower end is formed into a dog 31 adapted to engage between the rack teeth as 32 of the flange 2. This dog is held in engagement by means of the flat spring 33, one end of which is secured to said standard and the other end of which presses against said hand lever.

Pivoted to the standard 29 there is a manual lever 34 which is formed with an outwardly extending arcuate arm 35, whose free end is bifurcated, forming the fingers 36, which embrace the bracket 37 fixed upon the outer end of the fuel pipe 6. The bracket 37 has the laterally extending pins 38 which extend through the oblong bearings 39 provided in the fingers 36.

The upper end of the standard 29 is formed into a segmental rack 40 with which the dog 41 is held in engagement by the pressure spring 42. The dog 41 is secured to the lower end of the rod 43 which works through a central bearing in the lever 34. The lower end of this bearing is enlarged providing a recess for the spring 42, which surrounds said rod 43 and works against the dog 41 to hold it in engagement with the rack 40. A thumb lever 44 is pivoted to the upper end of the lever 34 and is provided with a bearing 45 through which the upper end of the rod 43 extends and said rod is provided with a transverse pin 46 above the bearing 45. Normally the lever 34 is locked against movement by the dog 41. Said dog may be released by pressing the thumb lever 44 and the lever 34 may then be moved in either direction and this

will operate to move the fuel pipe 6 in the opposite direction. It is thus obvious that the port 24 may be brought into or out of registration with the fuel inlet port 23 and may be locked in said position. When the fuel pipe 6 is moved inwardly the port 24 will be brought into registration with the port 23 and fuel will be admitted into the fuel pipe 6 and will pass along through said pipe and out through the ports 16 into the passageway 10. When said fuel pipe is moved inwardly as explained the nozzle tip 13 will be unseated from the seat 47, of the nozzle casing and will permit the passage of the fuel through into the mixing chamber 11. Meanwhile steam is admitted through the passageway 20 into the chamber 8 and it surrounds said fuel pipe and heats the same and the contents thereof and passes thence through the spiralled grooves 15 and 16 is thereby given a whirling motion and thereafter it catches up the fuel and carries it on through into the mixing chamber 11. This steam is under considerable pressure and the mixture strikes against the vanes 18 of the agitator 17 and causes said agitator to rotate rapidly and further mix the steam and fuel with the auxiliary air admitted through the ports 19, and with the gas taken in through the conduit 25, thus forming a highly combustible mixture which is discharged out through the nozzle 12 into the combustion chamber. In case it is desired to use gas as a fuel instead of oil, the lever 30 is operated to release the dog 31 from the teeth 32 and the burner casing and fuel pipe 6 are then turned within the shell 1 until the ports 23 and 24 are brought into alignment with the gas inlet 21 and the burner is then operated as above explained. It is obvious however that when the burner is adjusted to use gas as a fuel the conduit 25 will be out of connection with the gas inlet 26 as there will be no supplemental gas supplied to the burner. The outer end of the fuel pipe is normally closed by means of a valve 48, but when it is desired to clean out the burner the lever 34 is adjusted to bring the port 24 out of registration with the port 23 which will also operate to close the seat 47 by setting the tip 13 therein. The valve 48 is then opened and the steam admitted into the chamber 8 will pass through grooves 15 and enter the fuel pipe through the ports 16 and will be blown out through said pipe 6 thus cleaning the same out.

In Figure 11 I have shown a modified form of burner specially designed for use on locomotives. This form of burner is similar to the form shown in the other figures, excepting as to the parts shown in section. In this form of burner there is a single fuel oil inlet 49 and a single steam inlet 50. In this form the burner casing

and nozzle casing are formed integrally and designated by the numeral 51. Fastened to the outer end of this casing there is a depending arm 52 and pivoted to the free end 5 thereof is the bell crank 53. One arm of this bell crank is bifurcated forming the fingers 54 which embrace the bracket 37 and have the oblong slots 55 forming bearings through which the pins 38 extend. The fuel 10 oil pipe 6 may be moved back and forth, in an obvious manner, through a suitable manipulation of the bell crank 53 to carry the port 24 into or out of registration with the fuel inlet 49. The casing 51 is provided 15 with a flange 56 provided for the purpose of securing the burner to the fire box of the locomotive.

What I claim is:

1. A burner including a casing having a steam chamber therein, a rotatable fuel pipe extending through the casing and chamber and provided with an inlet port, a steam inlet entering said chamber, a pair of fuel inlets carried by the casing, means for turning 25 the fuel pipe to align said port with either of said inlets, means for moving the fuel pipe to bring said port into or out of registration with the fuel inlet, aligned therewith.
- 30 2. A burner including a casing having a steam chamber therein, a rotatable fuel pipe extending through the casing and chamber and provided with an inlet port, a steam inlet entering said chamber, fuel inlets carried by the casing, means for turning the fuel pipe to align said port with either inlet, and for moving the fuel pipe to bring said port into and out of registration with the aligned fuel inlets, a nozzle carried by said casing, 35 through which the steam and fuel are discharged from said chamber and fuel pipe respectively.
3. A burner including a burner casing having a steam chamber, a nozzle casing 45 fixed to the burner casing and having a mixing chamber, said chambers being connected by a passageway, a fuel pipe extending through said steam chamber and provided with a port, a nozzle tip fixed to the inner 50 end of said pipe and located in said mixing chamber and provided with fuel ports, a steam inlet communicating with the steam chamber, a fuel inlet, means for moving the fuel pipe to bring the port therein into or 55 out of registration with the fuel inlet and at the same time to move said tip to correspondingly open and close said passageway.
4. A burner including a burner casing, a nozzle casing connected thereto and having 60 auxiliary air inlet ports, a fuel pipe extending through the burner casing into the nozzle casing, a steam inlet entering the burner casing, a fuel inlet through which fuel is admitted into said pipe, the discharge end of 65 said pipe being provided with discharge

ports through which fuel is discharged into the nozzle casing and also being provided with peripheral spiralled grooves through which steam is discharged into said nozzle casing and mingled with the fuel therein. 70

5. A burner including a burner casing, a nozzle casing connected thereto, a fuel pipe extending through the burner casing into the nozzle casing, a steam inlet entering the burner casing, a fuel inlet through which 75 fuel is admitted into said pipe, the discharge end of said pipe being provided with discharge ports through which fuel is discharged into the nozzle casing and also being provided with peripheral spiralled grooves 80 through which steam is discharged into said nozzle casing and mingled with the fuel therein and a rotatable agitator in said nozzle casing.

6. A burner including a burner casing, a 85 nozzle casing connected thereto and provided with auxiliary inlet ports, a fuel pipe extending through the burner casing into the nozzle casing, a steam inlet entering the burner casing, a fuel inlet through which 90 fuel is admitted into said pipe, the discharge end of said pipe being provided with discharge ports through which fuel is discharged into the nozzle casing and also being provided with peripheral spiralled grooves 95 through which steam is discharged into said nozzle casing and mingled with the fuel therein, and a discharge nozzle carried by said nozzle casing.

7. In a burner, a stationary shell having 100 two fuel inlets, a burner casing within the shell having a steam chamber and a fuel inlet port, means for moving said casing so as to bring said port alternatively into registration with said inlets, a steam inlet in communication with said steam chamber when either of the fuel inlets registers with said port, a fuel pipe extending through said casing and provided with a port and means for moving said fuel pipe to alternately bring 105 the port thereof into and out of registration with said fuel inlet port.

8. In a burner, a shell having two fuel inlets, a burner casing within the shell having a fuel inlet port, means for rotating said 110 casing so as to bring said port alternatively into registration with said inlets, and means for locking the casing against rotation relative to the shell.

9. In a burner, a stationary shell having a 115 fuel inlet, a burner casing, within the shell having a fuel inlet port, means for rotating said casing, so as to bring said port alternatively into and out of registration with said inlet, a fuel pipe extending through 120 the casing and provided with a port and means for moving said fuel pipe lengthwise so as to bring said ports into and out of registration.

10. In a burner, a casing having an inlet 130

- port, a fuel pipe extending through said casing and provided with a port and means for moving said fuel pipe lengthwise in the casing so as to bring said ports into and out of registration.
11. In a burner, a casing having a fuel inlet port, a fuel pipe extending through the casing and provided with a port, means for moving said pipe lengthwise in the casing to bring said ports into or out of registration and means for locking said fuel pipe against movement relative to the casing.
12. In a burner, a burner casing having an internal steam chamber, a nozzle casing connected to the burner casing and having an internal mixing chamber and a passageway connecting said chambers, a fuel pipe extending through the burner casing through which fuel is discharged into said mixing chamber, means through which steam is admitted to said steam chamber, means within said passageway for imparting a whirling motion to the steam entering the mixing chamber from the steam chamber, a rotatable agitator within said mixing chamber and a discharge nozzle carried by the nozzle casing.
13. In a burner for oil or gas, a nozzle casing, having an internal mixing chamber and provided with auxiliary air inlets, means
- for introducing steam and fuel into said mixing chamber and a rotatable agitator within said mixing chamber.
14. In an oil burner, a burner casing, a nozzle casing attached thereto, means for admitting steam within the burner casing, means for admitting oil into the nozzle casing, spiraled baffles imparting rotary motion to the steam as it passes from the burner casing into the nozzle casing, and a rotatable agitator for mixing the steam and fuel within the nozzle casing.
15. In an oil burner, a burner casing, a nozzle casing attached thereto, means for admitting steam within the burner casing, means for admitting oil into the nozzle casing, spiraled baffles imparting rotary motion to the steam as it passes from the burner casing into the nozzle casing, and a rotatable agitator for mixing the steam and fuel within the nozzle casing and a discharge nozzle carried by the nozzle casing.

In testimony whereof I have signed my name to this specification in the presence of two subscribing witnesses.

WILLIAM M. ONEY.
